(57) CLAIM

The ornamental design for the reusable box cover with carry straps and display pockets, as shown and described.

DESCRIPTION

FIG. 1 is a front perspective view of the reusable box cover with carry straps and display pockets showing my new design;

FIG. 2 is an alternate front perspective view thereof;

FIG. 3 is a top plan view with the flaps in the open position thereof;

FIG. 4 is a end elevational view, the opposite end being identical thereto;

FIG. 5 is a side elevational view, the opposite side being identical thereto; and,

FIG. 6 is an exploded view thereof.

The broken line showing of articles in FIG. 5, and an inside supported box in FIG. 6, is for illustrative purposes only and forms no part of the claimed design.
